DETACHABLE SHIELD FOR FOUNDATION GARMENTS

Edward R. Sutter, Chicago, Ill., assignor to Beau-T-Form Foundations, Inc., Chicago, Ill., a corporation of Illinois

Application May 29, 1943, Serial No. 488,958

7 Claims.

(Cl. 2—224)

The invention relates to a detachable shield for a foundation garment and has as a general object to provide a new and improved shield of the character described.

A more particular object is to provide a shield having downwardly depending portions to lie between the legs of the wearer and means anchoring around the leg holding each depending portion smoothly in position to prevent the chafing resulting from rubbing of the legs directly one on the other.

Another object is to provide a shield that is shaped between the legs, that is, a shield having a main or central piece conformed to the space between the legs.

Another object is to provide a shield that is yieldable through the center, that is, longitudinally in a front to rear direction.

A further object is to provide a shield having a longitudinally yieldable main or central piece and depending chafe preventing portions also yieldable in the same direction.

Still another object is to provide a shield of the character described having depending chafe preventing portions and means extending about the thigh of the wearer for anchoring the chafe preventing portions in position formed as integral extensions of the chafe preventing portions.

A further object is to provide a shield of the character described composed of but three pieces of material with all of the pieces yieldable only in one direction, that is, longitudinally of the central piece.

Other objects and advantages will become apparent from the following description taken in connection with the accompanying drawing, in which:

Fig. 1 is a perspective view of a shield embodying the features of this invention and illustrated in the position it assumes on a wearer.

Fig. 2 is a transverse sectional view taken approximately along the line 2—2 of Fig. 1.

Fig. 3 is a side elevational view.

Fig. 4 is a view on a reduced scale showing the shield spread out as nearly flat as possible.

While the invention is susceptible of various modifications and alternative constructions, it is here shown and will hereinafter be described in a preferred embodiment. It is not intended, however, that the invention be limited thereby to the specific disclosure made but on the contrary it is intended to cover all modifications and alternative constructions falling within the spirit

and scope of this invention as defined in the appended claims.

As shown herein for purposes of disclosure, the shield comprises generally a main or central piece, generally designated 10, means at the front and the rear for detachably securing the shield to a foundation garment, chafe preventing portions, generally designated 11, and anchoring means therefor, generally designated 12. The central piece 10, as best seen in Fig. 4, is shaped to conform to the space between the legs to have the shield fit smoothly and comfortably and prevent folds of excess material which would itself chafe the wearer. To that end, the piece 10 is made narrowest at approximately the midpoint and flares curvedly outwardly in hour glass fashion in both directions from the midpoint. The piece is symmetrical about a longitudinal center line, but not about a transverse line through the midpoint, the flare being somewhat greater in the rear half of the piece to provide necessary fullness. By way of example, the piece 10 is at its front end 13 here shown as in excess of twice the width at the midpoint, while at its rear end 14 as in excess of three times the width at the midpoint.

In addition to being thus shaped, the piece 10 is so constructed or of such material as to have limited stretch in a longitudinal direction. Herein this is accomplished without the use of rubber by employing a material so woven or knit as to have this resiliency in a longitudinal direction. Preferably the material has substantially no give in a transverse direction. These characteristics of stretch in one direction and substantially no stretch in the opposite direction are obtained by the well known manner of weaving the material with the warp threads under tension and the woof threads laid in not under tension. In the present instance, the material is a jersey woven from threads composed of some one or more of the cellulose derivatives.

To support the central piece 10 detachably from a foundation garment, the front end 13 is provided with attaching means which are here shown as snap fasteners. Three apertured halves 15 of such fasteners are here shown and they are secured in well known manner directly on the piece 10, which near the edge of the end is reinforced by a tape 16. Cooperating with the apertured halves 15 of the snap fasteners are three headed halves 17 secured on a strip 18 usually secured as by sewing to the foundation garment. At the rear, the piece 10 has, at each corner, an integral and narrow extension 19 by

means of which the rear of the shield is attached to and supported by a foundation garment. Attaching means, again shown as snap fasteners, are provided with each extension carrying at its end an apertured half 20 of such snap fastener. Each extension 19 is at the point of attachment of the fastener reinforced with a piece 21 of non-stretchable material. Cooperating with each half 20 is a headed half 22 secured on a tab 23 adapted to be attached to the foundation garment as by sewing. The employment of the integral extension 19 of the stretchable material results in a more uniform yield of the shield with consequent increased comfort; the extensions do not deteriorate when washed as does elastic and there is a saving of both rubber and labor.

A foundation garment in performing its function of slenderizing the hips and upper thigh naturally presses the flesh of the thigh inwardly. Even in the case of a woman of average build, and particularly in stout and fat women, this causes the flesh on the inside of the thighs to rub together in direct contact and chafe. To prevent such direct contact of the flesh is an important feature of this shield. This function is performed by the portions 11. One such portion is attached to each curved side of the central piece 10 to depend therefrom and lie between the thighs of the wearer when the shield is being worn. With the rubbing to which the portions 11 are subjected while the wearer of the shield is walking, there is a great tendency for the portions to fold or roll up, which then is worse than no portions 11 at all. To prevent this the anchoring means 12 are provided. The means 12 extend about the thighs of the wearer anchoring the portions 11 firmly in position thus holding them against folding or rolling and also against sliding relative to the flesh of the thighs.

Though each chafe preventing portion and the anchoring means therefor might be formed in a variety of ways, they are for economy and smoothness of fit formed from a single piece of material 24. This piece of material has a straight lower edge 25 throughout its length with a multiple curved top edge. The middle approximate one-third of the piece of material, as best seen in Fig. 1, has a concavely curved top edge 26, that is, the middle one-third of the piece of material 24 is narrowest at its approximate midpoint and then curves upwardly to apexes 27, where the piece is of maximum width, so that it may follow the central piece 10 from its low midpoint upwardly to its ends and still hang smooth and unwrinkled when the shield is in worn position, as shown in Figs. 1 to 3. Each piece of material 24 is throughout the length of the curved 26 sewn by an external "Merrow" seam 28 to one curved side of the central piece 10.

From the apexes 27 each piece of material is here shown as curving sharply inwardly so as to form generally triangular shaped extensions 29 and 30 integral with the chafe preventing portion 11. These extensions are of such length as to enable them to extend around the thigh of the wearer and to be secured together on the outside of the thigh. On their free ends, the extensions 29 and 30 carry cooperating fastening means which herein take the form of cooperating halves 31 and 32 of snap fasteners. Herein two such snap fasteners are shown and each extension is at its free end, over a length sufficient to accommodate both snap fasteners, reinforced with a piece 33 of suitable non-stretchable material.

Like the piece 10, each piece of material 24, forming the chafe preventing portion 11 and the anchoring means therefor, has a limited stretch longitudinally, and preferably only longitudinally. Normally and preferably, the piece 24 is made of the same material as the piece 10. In this way the portions 11 are yieldable in the same direction and to the same extent as the piece 10 and thus, especially in view of their attachment by the "Merrow" seam, do not interfere with the longitudinal yielding of the central piece. This longitudinal stretch of the piece 24 also provides the circumferential stretch desirable in the anchoring means. The size of the shield worn should be chosen with a view to having the extensions 29 and 30 and the portion 11 partially stretched when the shield is put on. In this way not only is a smooth fit of the portions 11 assured but assurance is given that the friction between the flesh and the portion 11, when thus held, will be sufficiently greater than the friction between the smooth, slippery surfaces of the two chafe preventing portions 11 to assure that all relative movement resulting from walking of the wearer takes place between the portions and not between a portion and the thigh that it covers.

The shield is throughout its peripheral edges bound in a suitable manner with the bottom edge 25 of each piece 24 preferably bound by a stitching of the type employed in a "Merrow" seam in order not to destroy or interfere with the circumferential stretch of the anchoring means.

It is believed apparent from the foregoing that I have perfected a vastly improved, detachable shield for a foundation garment. This shield has a shaped construction to eliminate all excess material that might either bulk or be uncomfortable. At the same time the shield allows of complete freedom of action because of the novel use of stretchable material. Above all, the construction of the shield assures that the chafe preventing portion remains smoothly and firmly in position.

I claim as my invention:

1. A detachable shield for a foundation garment comprising, in combination, a central piece of material extending from front to rear of the shield and stretchable in that direction, said piece being narrowest at an intermediate point and becoming progressively wider in both directions away from the intermediate point, means at each end of said piece adapted to cooperate with means on the front and the back of a foundation garment for removably attaching said piece to the garment, an elongated piece of material sewn to each side of said central piece to depend downwardly therefrom between the thighs of the wearer when the shield is suspended from a foundation garment, each of said elongated pieces having a top edge portion curving upwardly at its ends and likewise stretchable in the same direction as said central piece to which it is sewn, and means adapted to fasten around the thigh of the wearer for anchoring said elongated pieces in position.

2. A detachable shield for a foundation garment comprising, in combination, a central piece of material extending from front to rear of the shield, said piece being narrowest at an intermediate point and becoming progressively wider in both directions away from the intermediate point, means at each end of said piece adapted to cooperate with means on the front and the back of a foundation garment for removably attaching said piece to the garment, and means

anchoring about each thigh of the wearer including an intermediate portion having an edge curving upwardly from an intermediate point and sewn one to each side of said central piece to depend downwardly between and partially around the thighs of the wearer.

3. A detachable shield for a foundation garment comprising, in combination, a shaped central portion extending from front to rear of the shield and stretchable in that direction, said portion being narrowest at an intermediate point and becoming progressively wider in both directions away from the intermediate point, means at each end of said portion adapted to cooperate with means on the front and the back of a foundation garment for removably attaching the shield to the garment, and means adapted to anchor about each thigh of the wearer including an intermediate portion depending from each side of said shaped central portion to lie between and partially around the thighs of the wearer when the shield is suspended from a foundation garment, the intermediate portion of said last mentioned means in particular being stretchable circumferentially to yield with said central portion.

4. A detachable shield for a foundation garment comprising, in combination, a central piece of material extending from front to rear of the shield, said piece being narrowest at an intermediate point and becoming progressively wider in both directions away from the intermediate point, means at each end of said piece adapted to cooperate with means on the front and the back of a foundation garment for removably attaching said piece to the garment, and a single piece of material sewn intermediate its ends and along its top edge one to each side of said central piece to provide a chafe preventing portion depending downwardly between the thighs of the wearer and integral portions of the same material adapted to extend around the thigh of the wearer for anchoring the chafe preventing portion securely in position.

5. A detachable shield for a foundation garment comprising, in combination, a central piece of material extending from front to rear of the shield, said piece being narrowest at an intermediate point and becoming progressively wider in both directions away from the intermediate point, means at each end of said piece adapted to cooperate with means on the front and the back of a foundation garment for removably attaching said piece to the garment, and two similar pieces of material each integral and secured to a side

of said central piece and adapted to anchor about a thigh of the wearer, each piece of material having an intermediate portion provided with a concavely curved upper edge and end portions of the same material for extending around the thigh of the wearer.

6. A detachable shield for a foundation garment comprising, in combination, a central piece of material extending from front to rear of the shield, said piece being narrowest at an intermediate point and becoming progressively wider in both directions away from the intermediate point, means at each end of said piece adapted to cooperate with means on the front and the back of a foundation garment for removably attaching said piece to the garment, and a single elongated piece of material secured to each side edge of said central piece, each of said pieces secured to said central piece having a straight bottom edge and a multi-curved top edge including a concavely curved top edge portion secured to one side of said central piece and defining an intermediate depending portion lying between and partially around the thighs of the wearer when the shield is suspended from a foundation garment and tapering integral extension portions adapted to extend around the thigh of the wearer for anchoring the chafe preventing portion against rolling and folding.

7. A detachable shield for a foundation garment comprising, in combination, a central piece of material extending from front to rear of the shield and stretchable in that direction, said piece being narrowest at an intermediate point and becoming progressively wider in both directions away from the intermediate point, means at each end of said piece adapted to cooperate with means on the front and the back of a foundation garment for removably attaching said piece to the garment, and a single elongated piece of material secured to each side edge of said central piece, each of said pieces secured to said central piece being stretchable longitudinally having a straight bottom edge and a multi-curved top edge including a concavely curved top edge portion secured to one side of said central piece and defining an intermediate depending portion lying between and partially around the thighs of the wearer when the shield is suspended from a foundation garment and tapering integral extension portions adapted to extend around the thigh of the wearer for anchoring the chafe preventing portion against rolling and folding.

EDWARD R. SUTTER.
